EVERETT J. COOK, OF TOLEDO, OHIO, ASSIGNOR, BY MESNE ASSIGNMENTS, TO THE DURA COMPANY, OF TOLEDO, OHIO, A CORPORATION OF OHIO

WINDOW-CONTROL MECHANISM

Application filed May 21, 1923. Serial No. 640,599.

This invention relates to window control mechanisms and relates particularly to devices for adjusting the sliding windows of motor vehicles. The invention may be regarded as an improvement upon the disclosure of applicant's copending application Serial Number 618,736.

Said invention consists in the structural features and arrangement of parts herein-
10 after fully set forth.

In the drawings:—

Figure 1 is an interior view of an automobile door equipped with the improved control mechanism;

15 Figure 2 is a view similar to Figure 1 but showing the lifter drawn to an enlarged scale;

Figure 3 is a bottom plan view of the same, partly in section;

20 Figure 4 is a vertical sectional view on line 4—4 of Figure 2.

In these views, the reference character 1 designates an automobile door having in its upper portion a window opening 2 and provided with a closure for said opening having the nature of a vertically slidable glass plate 3. Said plate, when lowered, is adapted to enter a well or chamber 4 formed in the lower portion of the door. Across the door, just 30 below the window opening, is extended the usual lock board 5 and to said board there is secured a depending sheet metal bracket 6. Said bracket is formed below the lock board with a circular opening, the margin of which 35 forms an internal gear 7. With said gear there is meshed an external gear 8 which is of slightly less diameter and which may also be a sheet metal stamping. The gear 8 is journaled upon an eccentric portion 9 of a shaft 40 10 transverse to the bracket 6, the eccentricity of the shaft portion 9 being equal to one half the difference in diameter of the gears 7 and 8 so that the smaller or external gear is in mesh with the larger or internal gear, the point of engagement rotating with the eccentric 9 as the shaft 10 is turned. Said shaft is journaled in a bushing 11 which is 45 rigidly mounted in an opening of an auxiliary bracket plate 12 riveted at its upper and lower ends to the main plate 6 as indicated

at 13, the end portions of said auxiliary plate being bent slightly so as to space the main body of said plate from the bracket 6. Between the plates 6 and 12 there is spirally coiled a spring 14, the inner end of which is 55 anchored to the plate 12, while its outer end hooks beneath a control arm 15 which is also mounted loosely upon the eccentric 9 and is riveted to the gear 8, as indicated at 16. 17 is an actuating handle for the shaft 10 mounted upon said shaft adjacent the free end of the bushing 11.

In the operation of the described invention, when the shaft 10 is rotated by the handle 17, the gear 8, owing to its eccentric 65 mounting, travels orbitally in constant mesh with the internal gear 7. Owing to the slight difference in diameter between the two gears, the smaller gear will advance rotatively only a small fraction of a revolution for 70 each bodily actuation of said gear through a complete turn. Thus, by employment of the proper predetermined ratio between the two gears, the smaller one, carrying the arm 15 is angularly shifted responsive to a predetermined 75 number of turns of the crank handle, sufficiently to raise or lower the glass through the desired distance. The spring 14 exerts a constant upward effort upon the arm 15 such as to substantially counterbalance the weight 80 of the closure 3. The mechanism is inherently self locking so that the closure is firmly held in its desired adjustment. The bodily orbital travel of the arm 15 resulting from the mounting thereof upon the driven eccentric 9 does not appreciably interfere with a steady upward or downward actuation of the glass by the arm, since the diameter of 85 said orbital movement is very small as compared to the effective radius through which 90 the arm swings to shift the glass.

The described construction is desirably light and compact, possesses the advantages of a unitary mounting, and lends itself to quantity production at low cost, through the 95 use of sheet metal stampings for its main parts.

Because of its thinness the described lifter may be installed in doors where the clearance 100 at the inner side of the glass is quite small.

What I claim as my invention is:—

1. A window control mechanism comprising a pivotal control arm, and a pair of gears establishing a drive connection to said arm, one internally meshing with the other, said arm being rigidly carried by one of said gears and extending transversely of the axis thereof, and means for actuating said gear orbitally of the other gear in constant mesh therewith. 10
  2. In a window control mechanism, the combination with an actuating element, of an external gear rigidly connected to said element, said element extending transversely of the axis of said external gear, a stationary internal gear meshing with said external gear, and means for actuating the external gear bodily about the axis of the internal gear in constant mesh therewith. 15
  3. In a window control mechanism, the combination with a pivotal window control element, of an external gear rigidly secured thereto and extending transversely of the pivot, a plate supporting said element and forming an internal gear engaged by said external gear, and means carried by said plate for actuating said external gear bodily around the axis of the internal gear in constant mesh with the latter. 20
  4. In a window control mechanism, the combination with a window control element, of an external gear rigidly secured to said element, a plate, a stationary internal gear in mesh with said external gear, a shaft carried by said plate having an eccentric portion carrying said control element and external gear, and a drive means for said shaft. 25
  5. In a window control mechanism, the combination with the control element for a window, of a sheet metal bracket having an opening marginally forming an internal gear, an external gear secured to said element intermeshing with said internal gear, a plate carried by said bracket and spaced slightly therefrom, a shaft journaled in said plate having an eccentric portion mounting said external gear and control element, the eccentricity of said shaft being selected to maintain the external gear constantly meshed with the internal gear, actuating means for said shaft, and a spiral counter-balancing spring arranged between said main plate and auxiliary plate. 40
  6. In a window control mechanism, the combination with a pivotal control arm, of intermeshing internal and external gears, one of said gears being rigidly connected to said control arm and being movable orbitally of the other gear and said control arm extending transversely of the axis of said gear connected thereto. 45
  7. In a window control mechanism, the combination with a pivotal control arm, of an external gear rigidly connected to said arm and extending transversely of the pivot, 50
  8. In a window control mechanism, the combination with a window control element, of intermeshing internal and external gears, one of said gears being rigidly secured to said control element whereby the latter is movable bodily with the former, a rotatable shaft having an eccentric portion upon which said gear secured to said control element is journaled, and means for rotating said shaft. 55
  9. In a window control mechanism, the combination with a bracket adapted to be secured to and extend below the lock board of a vehicle door, a transverse shaft carried by said bracket and spaced from an edge of the lock board, a window control element, means for actuating said control element, including a toothed member pivoted on said shaft and secured to said control element, and a second toothed member formed integral with said bracket and meshing with said first mentioned toothed member and a spiral spring encircling said shaft below the lock board and mounted in close juxtaposition to said bracket, said spring being connected to said control element to normally swing the latter upwardly. 60
